SEWING AND TRIMMING MACHINE

Frederic M. Card, Bridgeport, Conn., assignor to
The Singer Manufacturing Company, Elizabeth, N. J., a corporation of New Jersey

Application May 12, 1936, Serial No. 79,231

4 Claims. (Cl. 112—127)

This invention relates to improvements in trimmer mechanisms and more particularly in trimmer mechanisms of sewing machines, the invention having for its primary object to provide durable actuating means for a trimmer mechanism adapted to effect the production of smoothly trimmed and sharply curved work-edges.

With the above and other objects in view, as will hereinafter appear, the invention comprises the devices, combinations and arrangements of parts hereinafter described in connection with the accompanying drawings which illustrate a preferred embodiment of the invention and in which:

Fig. 1 is a rear side elevation, partly in section, of a sewing machine provided with the improved trimmer-actuating mechanism. Fig. 2 is an enlarged front end elevation, of the machine, partly in section. Fig. 3 is a detail view in elevation of the trimmer-knife throw-in lever. Fig. 4 is a top plan view, partly in horizontal section, of the sewing machine and the trimmer-actuating mechanism combined therewith. Fig. 5 represents a substantially vertical section of the counter-shaft crank and pitman. Fig. 6 represents a longitudinal section of the crank-actuated pitman, taken substantially on the line 6—6 of Fig. 5. Fig. 7 represents a transverse section of the pitman, taken substantially on the line 7—7 of Fig. 6.

The present invention constitutes an improvement in the trimmer-actuating mechanism of the pending U. S. patent application of Roy Painter, Serial No. 66,012, filed Feb. 27, 1936. Referring to the drawings, the improved trimmer-actuating mechanism is illustrated as embodied in a sewing machine having a frame comprising a bed-plate 1, from one end of which rises a work-supporting post 2. Upon the opposite end of the bed-plate 1 is the supporting standard 3 of a bracket-arm 4 which terminates at its free end in a head 5 overhanging the work-supporting post 2.

Rotatably journaled in the bracket-arm 4 is a horizontally disposed main actuating shaft 6 carrying at one end a combined belt-pulley and balance-wheel 7. At its opposite end, the main shaft 6 is provided with a crank-disk 8 operatively connected to reciprocate a vertically disposed needle-bar 9 carrying at its lower end a needle 10. The needle-bar 9 is journaled for endwise reciprocation in suitable bearings provided in a swinging frame 11 pivotally hung at its upper end upon a fulcrum-pin 12 suitably secured in the bracket-arm head 5 so that the

frame 11 swings about an axis in parallelism with the axis of rotation of the main shaft 6. Swinging movements are imparted to the frame 11 by a crank-arm 13 at one end of a rock-shaft 14, journaled horizontally in the bracket-arm 4, as more fully illustrated and described in U. S. Patent No. 1,884,404, Oct. 25, 1932, W. C. VanNess et al. The needle 10 cooperates, in the formation of lock-stitches, with the usual loop-taker (not shown) disposed within the upper end of the frame post 2.

In the operation of the sewing machine, the work is continuously advanced by a feed-wheel 15 projecting through a suitably slotted throat-plate 16 secured upon the upper end of the work-supporting post 2, the line of feed lying in the vertical plane of lateral movement of the needle 10. The feed-wheel 15 may be rotated by any suitable actuating mechanism, the present feed-wheel actuating mechanism being similar to that disclosed in the above noted U. S. Patent No. 1,884,404. It will be understood that the needle 10, while in the work, moves laterally in the direction of feed and that the return movements of the needle are effected while out of the work, so that the feeding of the work is assisted by the needle. Opposed to the feed-wheel is a presser-roller 17 closely adjacent to and at one side of the plane of needle-reciprocation, said presser-roller being carried by the lower end of the usual spring-depressed presser-bar 18 journaled for vertical movements in the bracket-arm head 5.

Secured, by screws 19, to the under side of the bracket-arm 4 is a trimmer bracket 20, providing bearings in which a knife-bar 21 is journaled for endwise reciprocation in a vertically inclined path. Carried by the lower end of the knife-bar 21 is a knife-holder 22 to which a work-severing element in the form of a straight-edge trimmer-knife 23 is secured by screws 24. While the cutting edge of the knife is straight, it is preferably inclined downwardly in the direction of feed, as illustrated in dotted lines in Fig. 2 of the drawings. The trimmer-knife 23 has a path of movement to sever the work substantially parallel to the line of seam formation and at the side of the path of the needle opposite to the presser-roller 17.

Suitably secured upon the knife-bar 21 is a collar 25 pivotally connected by a link 26 to an arm 27 of a bracket carried by the lower end of an actuator-bar 28. The actuator-bar 28 is confined to vertical reciprocation in suitable guide-slots provided in the bracket-arm head 5, said bar 28 having in its outer edge a notch 30 adapt-

ed to receive a coupling-pin 31. The coupling-pin 31 is carried by the free end of a crank-arm 32 extending horizontally forward from one end of a rock-shaft 33 disposed substantially parallel to the main shaft 6, said rock-shaft 33 being journaled for rocking and endwise movements in bearing-lugs 34 upon the machine bracket-arm, at the rearward side thereof.

At its end opposite to the crank-arm 32, the rock-shaft 33 has a circumferential groove 35 embraced by a suitably notched ear 36 upon a trimmer throw-out hand-lever 37. The hand-lever 37 is pivotally mounted upon a horizontally disposed fulcrum-screw 39 extending transversely of the main shaft 6 and threaded into a boss 40 upon the machine bracket-arm 4. The hand-lever 37 depends below the bracket-arm 4 so as to be conveniently accessible from the front side of the machine, said hand-lever being spring biased in a direction to releasably hold the coupling pin 31 in the notch 39 of the actuator-bar 28. A coil-spring 41 has its opposite ends connected to the bracket-arm 4 and to the knife-bar 21 to retract said knife-bar from operative position and thereby to raise the actuator-bar 28 when the hand-lever 37 is operated to disconnect the coupling-pin from the actuator-bar 28.

Suitably secured upon the trimmer-bracket 20, at the rearward side thereof, is an auxiliary bracket-plate 20' having its upper end spaced from the bracket 20 to receive therebetween a throw-in hand-lever for the trimmer-knife. This hand-lever comprises complementary lever-members 42, 43 pivotally mounted adjacent each other upon a stud-bolt 44. The member 42 has a laterally offset extension 45 overhanging the upper end of the lever-member 43 and to this extension is suitably secured a bent spring 46 bearing against the lever-member 43 below the pivotal axis thereof, said spring 46 functioning to yieldingly hold the lever-members 42, 43 against relative movement. The lever-member 43 of said hand-lever is yieldingly held by a spring 47 against a fixed stop-pin 48 extending inwardly from the bracket-plate 20' and determining the normal inoperative position of the hand-lever 42, 43. The offset extension 45 of the lever-member 42 is adapted to engage the upper end of the knife-bar 21 upon operation of the hand-lever 42, 43 and, as the bent spring 46 is stronger than the spring 47, the knife-bar 21 may be depressed by said hand-lever until the coupling-pin 31 enters the notch 39 in the actuator-bar 28. However, as the throw-in movement of the knife-bar 21 serves to initiate reciprocation of the actuator-bar 28 by the rock-shaft 33, the rapidly succeeding rising movement of the knife-bar 21 with the actuator-bar 28 reacts against the hand-lever extension 45 before the member 43 of the hand-lever can be released by the operator. It is at this time, primarily, that the spring 46 functions to permit the member 42 of the hand-lever to yield relatively to the member 43, thereby absorbing the vibratory action that would otherwise be transmitted to the hand of the operator. The hand-lever member 43 is, in the present instance, provided with a headed stud 49 which serves as a steady guide for the lower arm of the member 42 of said hand-lever. From the foregoing description it will be understood that the trimmer-knife carrying bar 21 may be connected to and disconnected from the rock-shaft 33 at the will of the operator during the operation of the machine.

Extending rearwardly from the rock-shaft 33 and rigidly secured thereto is a forked rock-arm 50, the spaced members 51 and 52 of which are provided with horizontally aligned apertures slidably receiving a pin 53 disposed substantially parallel to the rock-shaft 33. The pin 53 has a longitudinal bore 54 preferably receiving a wick 55, said bore 54 being intersected by a plurality of radial ducts 56 provided in said pin to conduct lubricant to the bearing faces in the 10 rock-arm members 51 and 52 for the pin 53.

Rigidly secured by a screw 57 upon the slide-pin 53, between the rock-arm members 51, 52, is the apertured lower end of a vertically disposed pitman 58. At its opposite end, the pitman 58 is apertured to pivotally embrace a crank-pin 59, extending from a crank-disk 60 at one end of a rotary counter-shaft 61. The pitman 58 is restrained against movement endwise of the crank-pin 59 by a collar 62 suitably secured upon 20 said crank-pin. The counter-shaft 61 is disposed substantially parallel to the main shaft 6 and is journaled in flanged bearing-bushings 63 and 64 suitably secured in horizontally apertured lugs 65 and 66 of a bearing-bracket 67. The bracket 25 67 is secured by screws 68 upon the machine bracket-arm 4 so that the counter-shaft bearing-lugs of said bracket 67 extend rearwardly from the bracket-arm 4.

Suitably secured upon one end of the counter-shaft 61 is a grooved pulley 69 connected by a belt 70 to a pulley 71 carried by the rotor-shaft 72 of an electric motor 73. The electric motor 73 is mounted upon a bracket 74 secured by screws 75 upon the rearward side of 35 the supporting standard 3 of the sewing machine bracket-arm, said electric motor 73 being preferably provided with an electric-current controlling switch 76. The pulleys 69 and 71 are preferably proportioned so that the counter-shaft 40 61 is rotated at a lower rate of speed than the speed of rotation of the rotor-shaft 72.

In order to supply lubricant to the counter-shaft bearings, the bracket-lugs 65 and 66 are each provided with upstanding and vertically 45 apertured bosses 77, the apertures 78 in said bosses (Fig. 5) being aligned with lug-apertures 79 forming lubricant wells below the bushing-apertures in said lugs. Each bushing 63 or 64 is diametrically apertured to provide a restricted 50 duct 80, connecting the boss-aperture 78 with the shaft-bearing face of the bushing, and a larger duct 81 aligned with the lug-well 79. Preferably, a wick 82 is disposed in the well 79 and extends through the bushing-duct 81 into contact with the counter-shaft 61. The boss-aperture 78 is yieldingly closed at its upper end by a suitable spring-pressed valve 83, while the bushing, 63 or 64, is provided in its shaft-bearing face with intersecting spiral grooves 84. Oil 60 introduced into the boss-aperture 78, through the valve 83, passes through the ducts 80 and 81 into the well 79, from which it is conducted by the wick 82 to the shaft and is distributed by the bushing-grooves 84 lengthwise and circumferentially of the shaft-bearing face of the bushing.

The pitman 58 is provided longitudinally thereof with a bore 85 (Fig. 6) of which the upper end is enlarged to form a reservoir 86 adjacent the crank-pin 59. Intersecting the lower portion of the reservoir 86 is a transverse pitman-bore 87 connecting said reservoir with the crank-pin bearing face of the pitman. Disposed in the transverse bore 87 is a wick 88 in wiping engage- 75

ment with the crank-pin 59. The upper end of the reservoir is, preferably, yieldingly closed by a spring-pressed valve 89, while the lower end of the pitman-bore 85 is alined with a radial duct 90 provided in the tubular slide-pin 53.

Partly embracing the crank and pitman connection between the counter-shaft 61 and the rock-arm members 51, 52, is an oil-guard bracket 91 which is substantially C-shaped in vertical section, said bracket having a laterally extending shank 92 secured by screws 93 to the under side of the bracket-lug 65. The lower portion of the bracket 91 has side walls 91', thereby to provide a well for collecting lubricant thrown off by the actuating mechanism embraced by the bracket.

From the foregoing description, it will be understood that when the electric motor 73 is in operation, the rocker comprising the rock-shaft 33 and its crank-arms 32 and 50 is continuously actuated, the reciprocation of the trimmer-knife 23 being dependent upon whether or not the coupling pin 31 is in operative engagement with the actuator-bar 28. By swinging the hand-lever 37 to the right, as viewed in Fig. 1, the rock-shaft 33 is shifted endwise to disconnect the coupling-pin 31 from the actuator-bar 28. The slide-pin 53 connection between the pitman 58 and the rock-arm 50 leaves the pitman 58 unaffected by the endwise movements of the rock-shaft 33.

It will be further understood that the trimmer-knife 23 may be rendered inoperative by disconnecting the electric motor 73 from its source of power, whereby the sewing machine may be operated without actuating any portion of the trimmer mechanism. On the other hand, the trimmer mechanism and the work-feeding mechanism of the sewing machine may be caused to operate conjointly, without stitching, by merely removing the needle 10 from the needle-bar.

Having thus set forth the nature of the invention, what I claim herein is:—

1. The combination with a sewing machine having a rotary actuating shaft, and stitch-forming mechanism deriving actuation from said shaft, of a trimmer mechanism comprising a reciprocatory trimmer-knife actuating bar, a driving shaft rotatable independently of said sewing machine actuating shaft, a counter-shaft operatively connected to rotate with said driving shaft, a two-armed rocker having one arm operatively connected to said trimmer-knife actuating bar, an actuating member pivotally connected to the

other arm of said rocker, and means carried by said counter-shaft for actuating said member.

2. The combination with a sewing machine having a rotary actuating shaft, and stitch-forming mechanism deriving actuation from said shaft, of a trimmer mechanism comprising a reciprocatory trimmer-knife actuating bar, an electric-motor operable independently of said sewing machine actuating shaft, a counter-shaft, driving connections for rotating said counter-shaft from said electric motor, a crank-member carried by said counter-shaft, a rock-shaft having a plurality of crank-arms, one of said crank-arms being operatively connected to said trimmer-knife actuating bar, and a pitman connecting the counter-shaft crank-member and the other arm of said rock-shaft.

3. The combination with a sewing machine having a rotary actuating shaft, and stitch-forming mechanism deriving actuation from said shaft, of a trimmer mechanism comprising a reciprocatory trimmer-knife actuating bar, a rocker shiftable lengthwise of its pivotal axis into and out of operative engagement with said bar, manually operable means for axially shifting said rocker, a driving shaft rotatable independently of said sewing machine actuating shaft, a counter-shaft operatively connected to said driving shaft, and an axially shiftable pivotal connection between said rocker and said counter-shaft.

4. The combination with a sewing machine having a frame including a work-support and a bracket-arm overhanging said work-support, and stitch-forming and work-feeding mechanisms carried by said frame, of a trimmer mechanism comprising a reciprocatory trimmer-knife actuating bar mounted in said bracket-arm, an endwise shiftable rock-shaft journaled in said bracket-arm, a crank-arm carried by said rock-shaft adapted to be coupled to and disconnected from said actuating bar, an electric motor mounted upon said frame and having a rotor shaft, a counter-shaft journaled upon said bracket-arm, driving connections between said rotor and counter-shafts, a crank-member carried by said counter-shaft, a second crank-arm carried by said rock-shaft, a pitman connection between said crank-member and said second crank-arm providing for endwise movements of said rock-shaft, and means for endwise shifting said rock-shaft.

FREDERIC M. CARD.
